EXPANSION JOINT

Robert G. Le Tourneau, Peoria, Ill., assignor to
R. G. Le Tourneau, Inc., a corporation

Application October 25, 1941, Serial No. 416,515

1 Claim. (Cl. 94—10)

This invention comprises improvements in expansion joints, and in particular the invention is directed to a unique expansion joint for use between sections of concrete in floors, sidewalks, curbs or the like, to prevent cracking of the sections upon expansion beyond normal dimensions and to enclose the gap between sections at all times and especially upon contraction to dimensions below said normal.

The principal object of the invention is to provide an expansion joint which in itself is solid and relatively non-expansible, being constructed preferably of metal but arranged to permit of free expansion or contraction of adjacent concrete sections while at all times maintaining the expansion gap covered.

Another object of the invention is to provide, in novel assembly, a permanent form for concrete slabs, and expansion joints, the latter initially functioning as form members.

An additional object is to provide a novel combination which comprises adjacent concrete slabs or sections and a joint in the form of an I-beam connecting the same; the flanges of the beam overhanging adjacent edges of said sections and adjacent ends of said sections being normally spaced from the beam web.

A further object of the invention is to provide a method of constructing a concrete floor or the like which comprises the steps of establishing a form which includes spaced parallel I-beams disposed with the beam flanges horizontal, and then pouring fresh concrete into the form and entirely filling the space between said flanges.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claim.

In the drawing similar characters of reference indicate corresponding parts in the several views:

Figure 1 is a plan view of the combination permanent form and expansion joints, a portion only of the form being filled with concrete.

Figure 2 is a fragmentary sectional elevation, showing a concrete slab in the combination form immediately after pouring.

Figure 3 is a fragmentary sectional elevation showing the retraction of adjacent ends of adjacent slabs from the web of the intermediate expansion joint.

Figure 4 is an elevation of a curb, partly in sec-

tion, illustrating the invention as arranged for use as a curb expansion joint.

Figure 5 is a cross-section on line 5—5 of Fig. 4.

Referring now more particularly to characters of reference on the drawing, and particularly at present to the embodiment shown in Figs. 1—3, inclusive, of the drawing, this embodiment discloses the combination in unitary assembly of the permanent form and expansion joints.

This assembly comprises a bordering form for a floor area or the like, the bordering members 1 being connected together at adjacent ends and being of I-beam configuration in cross section, with the beam web 2 disposed vertically. This bordering form is disposed on the ground G, which has previously been prepared and leveled, and a multiplicity of downturned hooks 3 project laterally inwardly from the webs 2 in a substantially horizontal plane some distance above the ground.

A plurality of I-beams 4 which initially serve as form members and subsequently as expansion joints, as will hereinafter appear, are rigidly connected to each other and to the bordering form in such relation as to provide rectangular sections 5 within the form; these I-beams 4 being disposed in the same plane as the form and with their webs 9 vertical.

The members comprising the combination bordering form and expansion joints are preferably connected together at points of abutment by welding.

When the combination bordering form and expansion joints is in place, each section 5 is poured with fresh concrete to produce a slab 6; the fresh concrete when poured entirely filling the space between the upper and lower flanges 7 and 8 of the adjacent I-beams and extending into full contact with the beam webs 9 thereof.

As the concrete dries and sets there is a temperature loss resulting in slight contraction of the slab which causes the edge portion of the same to pull away a short distance from the web 9 of the adjacent expansion joints, leaving a space 10 therebetween, as clearly shown in Fig. 3. As the edge portions of the slab retract from webs 9 with setting of the concrete, said edges also retract relative to the flanges 7 and 8, leaving depressions 11 beyond the side edges of said flanges.

With the expansion joint disposed as above, and after setting of the concrete, the slabs 6 can either expand or retract from normal, being

free to move toward or away from webs 9. The flanges 7 and 8 at all times maintain the gap between adjacent slabs enclosed, preventing the entry of debris or the like into spaces 10, which would be undesirable.

The concrete slabs cannot separate from the bordering members 1 for the reason that hooks 3 assure against any separation thereof; all compensation for expansion and contraction being accomplished through the medium of the I-beam expansion joints 4 which are connected between said bordering members 1.

In the embodiment shown in Figs. 4 and 5 the expansion joint is here designed particularly for use in connection with sidewalk curbs or similar structures. The curb type expansion joint includes a vertical plate or web 12 of substantially the cross sectional configuration of the curb 13; such web having a transverse flange 14 extending across the top of the web and down both sides thereof to ground level G₁, this flange projecting some distance beyond both sides of said web.

The above embodiment functions in the same manner as previously described, the freshly poured concrete engaging web 12 but retracting therefrom when the concrete sets, the flange 14 at all times covering and protecting the gap between adjacent sections of the curb.

From the foregoing description it will be readily seen that I have produced such a device as

substantially fulfills the objects of the invention as set forth herein.

While this specification sets forth in detail the present and preferred construction of the device, 5 still in practice such deviations from such detail may be resorted to as do not form a departure from the spirit of the invention, as defined by the appended claim.

Having thus described my invention, what I 10 claim as new and useful and desire to secure by Letters Patent is:

A combination permanent form and expansion joint for a plurality of rectangular concrete slabs, comprising a rigid bordering frame rectangular in plan, said frame being of a height equal to the thickness of the slabs to be formed therein, a plurality of expansion joints rigidly and permanently connected with said bordering frame, separating the area within the latter into a plurality of rectangular slab receiving sections, the frame bordering at least one edge of each slab poured in said sections, and a plurality of longitudinally spaced anchoring elements rigid with and projecting inwardly from the bordering 15 frame intermediate the top and bottom thereof whereby to anchor the slabs at said edges to the bordering frame; said joints being I-beams arranged to freely receive, in the opposed channels thereof, the remaining edges of the slabs.

ROBERT G. LE TOURNEAU.
